UNITED STATES PATENT OFFICE

MILLER REESE HUTCHISON, OF WEST ORANGE, NEW JERSEY, ASSIGNOR, BY MESNE ASSIGNMENTS, TO ACOUSTIC PRODUCTS COMPANY, OF NEW YORK, N. Y., A CORPORATION OF DELAWARE

TUNED RADIAL HORN

Application filed August 4, 1927. Serial No. 210,550.

The invention relates in general to acoustic apparatus, and more particularly to a loud speaker or sound reproducer having faithful and pleasing sound reproducing characteristics.

5 Horn or pipe resonators do not have the property of resonating satisfactorily fractional harmonics or notes of lower pitch than the fundamental, while they do have the property of resonating quite readily harmonics or 10 overtones of higher pitch than the fundamental.

15 In loud speakers of the multiple horn type, therefore, in order to obtain notes of great purity throughout the entire musical scale and to reproduce music faithfully, it is desirable to select individual horns which have a fundamental period quite low in the musical scale or spectrum. However, in the case of 20 low pitch open end horns or pipes, these pipes or horns, while resonating all the desired musical notes most satisfactorily, are necessarily of comparatively great length and are therefore, unsatisfactory from a standpoint 25 of economy and appearance, especially for household use.

According to the present invention, a multiple horn type loud speaker is provided which is economical both as to space required 30 and as to manufacture, and which presents a neat and pleasing appearance. At the same time these desirable advantages are obtained, the loud speaker renders music of great purity of tone and of great fidelity and in general 35 gives most satisfactory results.

These results and advantages are obtained, in one form of the invention, by providing a central sound chamber or casing and a plurality of closed end individual pipe resonators communicating therewith, each pipe being tuned to a different fundamental note 40 of the chromatic scale. An electromagnetic receiver or telephone unit having a single flexible diaphragm may be connected to one 45 side of the chamber or casing and a bell or flare for delivering the sound may be connected to the other side. The flexible diaphragm readily vibrates in response to the different notes impressed thereon by the elec- 50 tromagnet to set the surrounding medium into

vibration and each fundamental note and its overtones will be readily resonated by the resonator tuned to the particular fundamental.

Various other features and advantages of 55 the invention will be apparent from the following particular description and from an inspection of the accompanying drawings.

Although the novel features which are believed to be characteristic of this invention 60 will be particularly pointed out in the claims appended hereto, the invention itself, as to its objects and advantages, the mode of its operation and the manner of its organization may be better understood by referring to the 65 following description taken in connection with the accompanying drawings forming a part thereof, in which

Fig. 1 is a section taken on the line 1—1 of Fig. 2; and

Fig. 2 is a section taken on the line 2—2 of Fig. 1.

In the following description and in the claims parts will be identified by specific names for convenience, but they are intended 75 to be as generic in their application to similar parts as the art will permit.

Like reference characters denote like parts in the several figures of the drawings.

Referring now to the drawing, the device 80 as shown comprises a generally cylindrical chamber or casing 1 which is preferably of small cubic content. Arranged radially around the casing are a plurality of pipes 2 having their outer ends 3 closed and having their inner ends 4 flattened in the direction of the axis of the cylindrical casing, so that the cross section throughout the entire length of each pipe is substantially constant. The pipes are of different lengths to resonate the 85 different notes of any desired musical scale, and are preferably arranged to resonate the notes of an octave in the chromatic scale, there being twelve pipes, one for each note in the octave.

Connected to one side of the chamber or casing 1 is an electromagnetic casing 5 which may be similar to the usual loud speaker telephone unit comprising the usual magnet 6 having a winding thereon and a diaphragm 100

7 secured in operative relation thereto. On the other side of the casing 1 from the telephone unit is secured a bell or flare 8 which operates to convey the sound waves which are 5 resonated by the pipes to the surrounding medium.

Sound pipes do not readily resonate the fractional harmonics below the fundamental, whereas they resonate quite readily the harmonics or overtones above the fundamental.

10 It is, therefore, of prime importance, in order to have pleasing reception, to make the pipes of such lengths that the octave covered thereby is comparatively low in a musical scale.

15 Pipes having closed ends have lengths equal to one-quarter the wavelength resonated, and therefore the pipes may be contained in a comparatively small space even though the fundamental notes are low in the musical 20 scale and the wavelengths long.

The chamber or casing is made of small cubic content so as not to have any critical period of its own within the range of audibility. The diaphragm is of such nature 25 as to respond readily and to vibrate to all the different audible frequencies.

It will be seen that the energy of complex wave form delivered to the electromagnet by the electric current will be reproduced 30 faithfully and will give a pleasing effect. Each note is readily transmitted by the flexible diaphragm and is readily resonated by some particular pipe or tube, the note then being delivered by the bell or flare into the 35 surrounding medium. Since each note impressed electrically upon the electromagnet is faithfully transmitted by the acoustic apparatus to the surrounding medium, the original quality of the sound delivered to the 40 electromagnet will be quite unimpaired by the acoustic apparatus and the result will be pleasing to the ear.

Although the apparatus has been described 45 as a loud speaker or reproducer and it is intended fundamentally, to be used as such, it will be appreciated that it may be used also as a transmitter. In this case its operation will be reversed, original music or other sound being delivered into the bell or 50 flare and causing variation in the current flowing through the windings of the receiver, as is well understood in the art.

While certain novel features of the invention have been shown and described and 55 are pointed out in the annexed claim, it will be understood that various omissions, substitutions and changes in the forms and details of the device illustrated and in its operation may be made by those skilled in the 60 art without departing from the spirit of the invention.

What is claimed is:

In a loud speaker, a cylindrical hollow casing of small cubic content, twelve sound 65 resonating tubes each arranged to resonate a

different note of the chromatic scale and disposed radially around said casing and communicating therewith, said tubes having closed outer ends and being flattened at their inner ends in the direction of the axis of the 70 cylindrical chamber, a sound propagator connected to the back end of said casing, and an outwardly flaring bell connected to the front end of said casing.

Signed at New York, in the county of New 75 York and State of New York, this 2d day of August, A. D. 1927.

MILLER REESE HUTCHISON.
